UNITED STATES PATENT OFFICE.

HOWARD S. KNEEDLER, OF PHILADELPHIA, PENNSYLVANIA.

DESIGN FOR TICKING OR SIMILAR FABRICS.

SPECIFICATION forming part of Design No. 17,573, dated August 2, 1887.

Application filed July 5, 1887. Serial No. 243,418. Term of patent 7 years.

To all whom it may concern:

Be it known that I, HOWARD S. KNEEDLER, a citizen of the United States, and a resident of Philadelphia, Pennsylvania, have invented 5 a new and original Design for Ticking or Similar Woven Fabrics, (Case A,) of which the following is a specification.

My design for ticking or other woven fabrics is fully illustrated in the accompanying drawings, in which—

Figure 1 is a view showing the general effect, and Fig. 2 is a view drawn to a larger scale and showing the details of the stripes.

My design comprises wide stripes A and narrow stripes B, alternating on a ground color, G.

The wide stripe A consists of a bar, a, having running through it at one side a light stripe, 4, with a central dark line, 5. On one side of the bar a is a dark stripe, 2, followed by a number of stripes, 6, which gradually merge into the ground color G. On the other side of the bar a is a dark stripe, 3, followed by a number of shading-stripes, 7, similar to the stripes 26, but narrower in width. The narrow stripe 25 B consists of a number of narrow dark bars, b, with intermediate light lines, 8.

I claim—

The design for ticking or other woven fabrics, said design comprising wide and narrow 30 stripes A and B on a ground, G, the wide stripes A consisting of a bar, a, having a lined light stripe, 4, running through it on one side and bordered with dark stripes 2 3, and shading-stripes 6 7, merging into the ground, while the 35 narrow stripe B consists of narrow dark bars with intervening light lines, all substantially as shown and set forth.

In testimony whereof I have signed my name to this specification in the presence of two sub- 40 scribing witnesses.

HOWARD S. KNEEDLER.
